(57) **CLAIM**

The ornamental design for an applanation lens cone for ophthalmic laser surgery, as shown and described.

DESCRIPTION

FIG. 1 is a perspective view, from above or an applanation lens cone for ophthalmic laser surgery showing my new design, with a plano-plano lens shown within;

FIG. 2 is a side elevational view thereof;

FIG. 3 is a bottom plan view thereof; and,

FIG. 4 is a top plan view thereof.
